Atty.

UNITED STATES PATENT OFFICE

2,644,499

ADJUSTABLE BENCH STOP

Henry H. Logan, Chicago, Ill.

Application June 3, 1950, Serial No. 165,996

3 Claims. (Cl. 144—308)

1

My invention contemplates and provides an improved bench stop.

An object of my invention is to provide a simple, sturdy and altogether practical bench stop that may be properly so utilized as to have no dulling effects upon tools appropriately applied to a work piece with which the bench stop is cooperating, and which, even if improperly used, can have but minimum dulling effects on such tools.

Another object of my invention is to provide a bench stop consisting essentially of a tightener-equipped stop-plate unit which, when occasion requires, may be very quickly removed from or restored to an elevator-equipped flush plate unit that is conformed and adapted for novel and effective cooperation with the stop-plate unit.

With the above and other objects in view, as will hereafter appear, my invention consists of certain novel features of construction, combinations and arrangements of parts hereinafter more fully described and illustrated in the accompanying drawings wherein like characters of reference denote like parts throughout the several views. In the drawings,

Fig. 1 is a side elevational view of a bench stop embodying my invention;

Fig. 2 is a top plan view thereof;

Fig. 3 is a front elevational view thereof; and

Fig. 4 is a perspective view of a modified stop plate unit.

Indicated by dotted lines at 11 is the wooden top of a bench with which the improved bench stop of my invention may be associated. The bench stop itself may be regarded as comprising, essentially, two units, i. e. an elevator-equipped flush plate unit and a tightener-equipped stop plate unit.

The elevator-equipped flush plate unit comprises the flush plate 12 adapted to be recessed into a front corner of its associated bench top 11, as shown. Plate 12 desirably is provided with suitable screw holes for the reception of wood screws 13 for securing the plate to the bench top. Such plate 12 desirably is provided, at or near one end thereof, with a downwardly projecting lip 14 adapted to engage a complementary table top recess to protect the screws from strains in transverse shear when the bench stop is in use. At the end thereof opposite the lip 14 the plate 12 is provided with a massive downwardly projecting flange 15. Such flange 15, being parallel to the lip 14, is adapted and intended to lie contiguous and alongside the adjacent end of the bench top 11. Such plate 12 and its in-

tegral parts 14 and 15 preferably are formed of a readily machined and corrosion resistant metal such as bronze. Massive flange 15 is intended to serve as a stop plate receiver and to that end is provided with an upwardly opening longitudinally extending slot 16, the flange being U-shaped with the open end of the U adjacent the plate 12 and the closed end away from the plate. The inner leg of the U-flange is secured to the plate 12 and the outer leg is spaced therefrom. The slot 16 desirably is somewhat narrow and quite deep and is spaced away from but parallel with the adjacent end edge of the bench top 11, as shown. Threadedly cooperating with the flange 15, and projecting upwardly into the slot 16 substantially midway between the ends of the latter, is an elevator screw 17. Screw 17 desirably is provided with a knurled or equivalent head facilitating its manual manipulation. Salient features 20 of the stop plate receiver afforded by U-flange 15 are the upwardly opening spaced-apart through notches 18 in the outer leg of the U. These notches 18, of which preferably there are two, are formed in that vertical wall of the slot 16 which lies away from the adjacent end edge of the bench top.

The tightener-equipped stop plate unit consists of a plate 19 and a pair of tightener screws 20, which serves both to guide and to hold the plate 13 in the flange 15. Plate 19, which is of such size and shape as to be fairly snugly but not tightly embraced by the walls of the aforementioned slot 16, desirably is formed of a relatively quite soft metal such as aluminum. Each of the tightener screws has threaded engagement with the stop plate 19 and, when the bench stop is in use, occupies but extends freely through one of the aforementioned upwardly opening notches 18. Screws 20 guide the plate 19 by preventing it from tilting on the single adjusting screw 17. Screws 20 hold the plate 19 against the outer leg of the U-flange 15 by being screwed into the plate so that the outer leg is clamped between the plate 19 and the enlarged heads on the screws. These enlarged heads are knurled to facilitate manipulation of screws 20. Elevator screw 17 has a knurled head for the same reason.

The bench stop just described has important advantages. It can be economically manufactured and easily installed upon a bench top. It will withstand long continued heavy service without becoming loosened with respect to the bench top. By virtue of the elevator screw 17 and the tightener screws 20, the stop plate 19 may be vertically adjusted and retained in slot 16 so as

to cooperate with any given piece of work, e. g. a thin board, so as practically to eliminate any chance of the cutting edge of a tool, such as a plane, from contacting the stop plate 19. However, if the cutting edge of such a tool should contact the stop plate 19, the result will be little or no dulling of that cutting edge by reason of the softness of the metal whereof the stop plate is formed.

A very important advantage of my improved bench stop is the ease and facility with which the stop plate unit may be detached from and restored to the flush plate unit, in a predetermined but none the less adjustable relationship to the flush plate unit, whenever occasion requires. In the use of the bench there will be occasions when the stop plate should be absent or be replaced with one such of specifically different conformation, e. g. the conformation depicted in Fig. 4. To remove the stop plate unit from the flush plate unit, the tightener screws 20 need be only slightly loosened; thereupon the stop plate unit readily may be withdrawn, as such unit from the flush plate unit. Moreover, a stop plate unit may be manipulated into appropriate cooperating relationship with the flush plate unit merely by guiding the lower edge of the stop plate 19 into the slot 16 and the shanks of the screws 20 into the notches 18, manipulating elevator screw 17 if and only if further vertical adjustment of the stop plate is desired, and then tightening the screws 20.

The shanks of the tightener screws 20 desirably have rather loose fits in their cooperating notches 18. One advantage of this loose fit of the screw shanks in the notches is that it permits but just a minute portion of one end of the stop plate to project above the upper surface of the flush plate unit whenever, as is sometimes the case, that is desirable.

The stop plate unit of Fig. 4 differs essentially from the stop plate unit of the preceding figures only in that the upper portion of that face of the stop plate 19 which is presented to the work is provided with integral extensions 19a diverging away from the stop plate in the form of a lazy V for cooperation with certain work pieces, e. g. a board disposed edgewise on the bench. That face of stop plate 19 which is presented to the work may have other special contours for suitable cooperation with certain work pieces.

Having thus illustrated and described a presently preferred embodiment of my invention, what I claim as new and desire to secure by Letters Patent of the United States is:

1. A bench stop comprising a plate to be secured to a bench top at one end thereof, a stop plate receiver carried by the plate at one end thereof and serving as a downwardly projecting flange adapted to lie contiguous and alongside the adjacent end of the bench top, an upwardly opening longitudinally extending slot formed in said receiver, an adjustable device associated with said receiver and operable to engage the lower edge of the hereinafter mentioned stop plate at a point intermediate the ends of said lower edge and intermediate the hereinafter mentioned vertically extending slots, a plurality of upwardly

opening spaced-apart vertically extending slots formed in the vertical wall of said slot which is to lie away from the bench end whereto the receiver is contiguous, and a stop plate unit, removable from and restorable to the receiver as such unit, comprising a stop plate receivable in said longitudinally extending slot and a pair of tightener screws each threaded into the stop plate and each adapted to occupy one of said vertically extending slots with a loose fit.

2. A bench stop comprising a bench member adapted to be attached to the bench and having a recess open at one end and closed at the other end, an elongated stop member loosely positioned in the recess so as to be capable of projecting beyond the bench member at the open end of the recess, a single adjusting member associated with the bench member at the closed end of the recess for varying the amount by which the stop plate projects beyond the bench member, and a pair of screws associated with the stop member and the bench member at opposite sides of the adjusting member to enable the stop member to be shifted by the single adjusting member, the screws projecting freely through the bench member and having enlarged heads on the outside of the bench member and threaded portions in threaded engagement with openings in the stop member, whereby the screws may be screwed into the stop member to hold the same by clamping the bench member between the enlarged heads and the stop member.

3. A bench stop comprising a bench member adapted to be attached to the bench and having a recess open at one end and closed at the other end, an elongated stop member loosely positioned in the recess so as to be capable of projecting beyond the bench member at the open end of the recess, a single adjusting element associated with the bench member at the closed end of the recess for varying the amount by which the stop member projects beyond the bench member, and a pair of screws associated with the stop member and the bench member at opposite sides of the adjusting element to enable the stop member to be shifted by the single adjusting element, the screws projecting freely through one member and having threaded portions in threaded engagement with openings in the other member and enlarged heads on the side of said one member away from said other member, whereby the screws may be screwed into said other member to clamp the members against one another.

HENRY H. LOGAN.
